Patented Jan. 2, 1973

225,741

ELECTRONIC DATA PROCESSING CONSOLE UNIT

Loring C. Bixler, Donald F. Lahey, and Edward R. Wiener, Binghamton, and Arnold M. Davis and Walter S. McCormick, Jr., Poughkeepsie, N.Y., assignors to International Business Machines Corporation, Armonk, N.Y.

Filed June 23, 1970, Ser. No. 23,906

Term of patent 14 years

Int. Cl. D14—02

U.S. Cl. D26—5

FIG. 1

FIG.2

FIG. 3

FIG. 1 is a front right perspective view of an electronic data processing console unit showing our new design for a console;

FIG. 2 is a rear right perspective of the electronic data processing console unit of FIG. 1;

FIG. 3 is a top plan view of the electronic data processing console unit of FIG. 1.

We claim:

The ornamental design for an electronic data processing console unit, as shown.
